DESIGN FOR A PROJECTOR

Thomas H. North, Bald Eagle, Minn.

Application February 15, 1937, Serial No. 67,662

Term of patent 14 years

To all whom it may concern:

Be it known that I, Thomas H. North, a citizen of the United States, residing at Bald Eagle, county of Ramsey, and State of Minnesota, have invented a new, original, and ornamental Design for a Projector, of which the following is a specification, reference being had to the accompanying drawing, forming part thereof:

I claim:

The ornamental design for a projector, as shown.

THOMAS H. NORTH.
